DEVICE FOR SORTING CARDS

Don H. Young, Athens, Ohio, assignor to The
McBee Company, Athens, Ohio, a corporation

Application March 18, 1947, Serial No. 735,491
5 Claims. (Cl. 129—16.1)

1

This invention relates to devices for sorting marginally punched record cards, checks and the like.

The present application is a continuation-in-part of my application for "Card Sorting Device," Serial No. 600,181, filed June 18, 1945, now Patent No. 2,555,666 dated June 5, 1951.

As set forth in my above identified application, a long sorting rod or needle, provided with a handle at one end, has been used for sequence sorting of marginally punched cards of the type shown in United States Patent No. 1,544,172, issued to A. Perkins on June 30, 1925. The operator grasps the handle and projects the other end of the needle or rod through selected, aligned punched holes of a stack of cards, which are then elevated and held in position suspended from the needle. Thereafter, the needle is jarred to insure the dropping from the stack of cards which had been previously notched in registry with the needle.

In view of their support at only one end during the card sorting operation, namely, at the handle end, prior needle arrangements are prone to flex or bend under the weight of the stack of cards suspended therefrom at a substantial distance from the handle point of support. Such flexure of the needle not only tends to deter separating of cards notched in registry with the needle, but also imposes a considerable card weight overhanging the single point of handle support by a substantial distance, or a moment arm, from the operator's hand and arm, requiring the application of excessive muscular strength during the sorting operation, with attendant fatigue. The overhanging weight of the cards on the needle from the single handle point of support also tends to cause the needle to tilt downward, allowing the cards to slide off its free end.

The present invention has for an object the provision of an improved sorting device of the general character referred to, in which the rod or needle can be supported at both ends during the sorting operation, with the device adapted for grasping by the operator's hand at a median point to enable a large stack of cards to be suspended from the needle or rod without its flexing and with the expenditure of a minimum of muscular effort.

Another object of the invention is to provide an improved device for sorting punched record cards and the like, in which the cards are prevented from inadvertent longitudinal removal from the needle or rod.

One form which the invention may assume is

exemplified in the following description and illustrated by way of example in the accompanying drawings, in which:

Fig. 1 is a perspective view of a device embodying the invention.

Fig. 2 is a perspective view of one type of marginally punched cards with which my improved device may be employed.

Fig. 3 is a side elevation of my improved device with portions broken away and in section to more fully disclose certain parts of the device and details of construction.

In the drawings, a record card 10, of the type commonly known as "Keysort" card, is disclosed which is used for record keeping and other purposes, being of the general type shown in the patent to A. Perkins, No. 1,544,172. The device illustrated in the drawings is to be used in connection with cards of this character, although it is obvious that various other types of punched cards can be sorted by means of the device.

Cards of the character illustrated in Fig. 2 are provided with marginally punched holes 11 which may be notched to provide a slot 12 to the edge 13 of the card to indicate a particular classification. Since the construction and use of cards of this character are well known, it is unnecessary to more particularly describe them.

The device for sorting marginally punched cards disclosed in the drawings includes a body or supporting handle 14 of generally bail-shaped form, composed of an intermediate longitudinally extending gripping portion 15 and a depending leg 16 at one end thereof, to the lower portion of which one end of a sorting needle or rod 17 is suitably secured, such rod extending in a longitudinal direction under and generally parallel to the gripping section 15. The body 14 may be made of two similar halves joined together by screws 18, or any suitable means. The forward ends of each body section have recesses 19 to provide spaced parallel arms 20 to which a pivot pin or pinte 21 is secured, mounting a supporting or latching leg 22 whose lower end has a hole or opening 23 into which the forward end of the sorting rod or needle 17 may extend, in order that the leg 22 may provide a support for such end of the needle or rod.

The pivoted supporting leg 22 has an inner upwardly extending operating finger 24, and also a rearwardly projecting stop finger 25. These parts are adapted to cooperate with and be engaged by a forward projection 26 of an operating lever 27 disposed within the body of the device and pivotally mounted upon a suitable pin or screw 28, which may also serve the purpose of joining the

two body sections together. The operating lever 27 is urged in an upward direction by a spring 29 suitably attached to the lower arm 30 of the lever 27 and to the pivoted supporting leg 22, the spring tending to swing the leg 22 inwardly to dispose its lower end over the sorting rod 17 and to swing the operating lever 27 upwardly to dispose its upper surface 27a in engagement with the underside of the top portion of the handle body 14, which locates the projection 26 in alignment with the leg stop 25.

A rod 31, integral with or otherwise secured to the operating lever 27, projects upwardly through the body recesses 19 and terminates in a thumb-piece or button 32 adapted to be engaged and depressed by the thumb of a person's hand gripping the longitudinal handle 15 of the body in using the device.

Normally, the spring 29 maintains the operating lever 27 in its upward position and the pivoted supporting leg 22 in an inward position with the needle 17 disposed within its lower hole or opening 23, thereby providing a two-point support for the needle, one furnished by the fixed leg 16 and the other by the pivoted leg 22. The pivoted leg cannot swing outwardly free of the needle, since its stop 25 engages the forward projection 26 on the operating lever 27. When it is desired to use the device for sorting a stack of cards, the gripping section 15 of the handle is grasped by the hand and the thumb employed to depress the thumb-piece 32, which shifts the forward projection 26 of the operating lever downwardly free from engagement with the stop 25 on the pivoted leg 22 and into engagement with the vertical operating finger 24. Such depression of the operating lever 27 causes its projection 26 to bear against the operating finger 24 and swing it downwardly, at the same time moving the lower portion of the leg 22 forwardly free from its initial position of disposition over the sorting needle 17, to a position disposed above the needle a distance greater than the distance between the punched holes 11 in the cards and their adjacent edges 13.

The needle 17 may then be placed through selected aligned holes in a stack of cards 10 and the pressure on the thumb-piece 32 released, which allows the spring 29 to reposition the pivoted leg 22 over the free end of the sorting needle 17 and reelevate the operating lever 27 until its upper surface 27a engages the handle, in which position the projection 26 is disposed in alignment with the stop 25 to prevent outward swinging of the leg 22. The cards 10 may now be elevated through elevating the sorting device, and the entire stack jarred, which allows any cards 10a which have been notched in registry with the needle to drop from the stack and holds the unnotched cards on the needle. Following removal of all of the notched cards 10a from the stack, the thumb may again depress the operating lever 27 to swing the pivoted leg 22 in an outward direction, to the dotted line position shown in Fig. 3, and the cards 10 may be removed from the needle.

It is to be noted that the needle 17 is supported at both of its ends, thereby minimizing, if not entirely eliminating, any tendency for the needle to deflect under the weight of the stack of cards suspended therefrom, and during the jarring operation, which permits the cards notched in registry with the needle to drop readily therefrom and out of the stack. It is also to be noted that no overhanging weight is imposed upon the

operator's hand, since it is centrally positioned on the upper longitudinal body portion 15 of the handle, or substantially directly above the cards, enabling the weight of the cards to be supported readily by the operator and with a minimum of muscular exertion and fatigue. It is further evident that the sorting rod or needle need not be maintained in a horizontal position, since the cards cannot slide lengthwise of the needle and off its free end. Any such sliding tendency results in engagement of the end card with the pivoted leg 22, which is held from outward swinging by contact of its upper stop 25 with the forward projection 26 on the operating lever 27. Removal of the cards can only be effected purposefully upon depression of the operating lever 27, to retract its forward projection 26 from alignment with the lever stop 25.

It is, accordingly, apparent that a comparatively simple and inexpensive device has been provided for sorting marginally punched cards, which may be operated with facility, with a minimum exertion of effort, and with assurance against inadvertent removal of unnotched cards from the needle.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A device for sorting punched record cards, checks and the like, including a longitudinally extending handle, a leg depending from said handle, a sorting rod secured at one end to said leg and extending under and substantially parallel to said handle, another leg pivotally mounted on said handle for swinging movement in a plane longitudinally of said rod to and from supporting engagement with the other end of said rod, said pivoted leg having an operating finger and a stop, an operating lever mounted on said handle and movable against said finger for swinging said leg out of supporting engagement with said rod, and a spring secured to said operating lever and pivoted leg for urging said pivoted leg toward supporting engagement with said rod and for urging said operating lever upwardly to a position wherein it is engageable with said stop to prevent movement of said pivoted leg from supporting engagement with said rod.

2. An impaling device comprising a body portion, an impaling needle supported at one end thereby, a keeper member pivotally supported by said body portion to pivot into and out of engagement with the other end of said needle, said member having means to engage said needle and to support the same and to retain impaled objects thereon, a lever pivotally supported by said body portion, means for manually pivoting said lever, a coil spring connected at one end to said keeper member and at the other end to said lever to urge the same in opposite directions and to urge said keeper member into engagement with said needle, stop means serving normally to retain said lever in a predetermined pivotal position, engaging means on said lever normally operable as a stop member for said keeper member, and engaging means on said keeper member operable, when said lever is manually actuated, to engage said engaging means on said lever and thereby pivot said keeper member out of engagement with said needle.

3. A device of the character described comprising a longitudinally extending handle, a leg depending from said handle, a sorting rod secured at one end to the leg, another leg pivotally mounted on said handle for swinging movement, said pivotally mounted leg having means provided at its free-swinging end to engage the sorting rod, and thereby support said rod under the weight of, and preclude disengagement of, sorted items, said pivotally mounted leg having an operating finger and a stop finger, an operating lever mounted in said handle and movable against said operating finger so as to pivotally swing the pivoted leg out of engagement with the rod, and a spring secured to said operating lever and pivoted leg for urging said pivoted leg back into engagement with said rod and to urge said operating lever upwardly to a position wherein it is engageable with said stop finger to prevent movement of said pivoted leg from supporting engagement with said rod.

4. A device of the character described comprising a substantially L-shaped body, the shank of which constitutes a handle, a rigid straight elongated rod rigidly supported by the leg of said body and extending parallel with the handle, a pivotally mounted keeper carried by the end of said handle and movable to and from the free end of said rod, said keeper having an operating finger and a stop finger, an operating lever mounted on said handle and movable against said operating finger for moving said keeper from the free end of said rod, and resilient means secured to said keeper and operating lever for urging said keeper toward said rod and for urging said oper-

ating lever upwardly to a position wherein it is engageable with said stop finger to prevent movement of said keeper from said rod.

5. In a device of the character described, a substantially L-shaped body, the shank of which constitutes a handle, a rigid straight elongated impaling needle rigidly supported by the leg of said body and extending parallel with the handle; a pivotally mounted keeper carried by the end of said handle and movable to and from the free end of said needle, said keeper having a stop finger and actuator finger, an actuator pivotally mounted on said handle and abutting said stop finger to preclude pivotal movement of the keeper, said actuator being movable from said stop finger to said actuator finger to move said keeper from said needle, and resilient means extending between said keeper and said actuator for normally retaining said keeper adjacent said needle and said actuator in contact with said stop finger.
